[57] CLAIM

The ornamental design for a lens for faucet handle and the like, as shown and described.

DESCRIPTION

FIG. 1 is a top plan view of a lens for faucet handle and the like showing my new design;

FIG. 2 is a side elevational view thereof; and

FIG. 3 is a cross sectional view thereof taken on line 3—3 of FIG. 2.

*Fig. 1.**Fig. 2**Fig. 3.*
